[57] CLAIM

[21] Appl. No.: 687,371

The ornamental design for a detachable luggage case for a motorcycle, as shown and described.

[22] Filed: May 17, 1976

DESCRIPTION

[51] Int. Cl. .... D3—01
[52] U.S. Cl. .... D87/5 F
[58] Field of Search .... D87/1 R, 5 R, 5 F, 5 G;
190/41 R, 60, 52; D12/158; 224/31, 32 A, 39,
42.01, 43, 44

FIG. 1 is a perspective view of a detachable luggage case for a motorcycle showing my new design.

FIG. 2 is a right end elevational view.

FIG. 3 is a top plan view.

FIG. 4 is a front elevational view.

FIG. 5 is a bottom plan view.

FIG. 6 is a rear elevational view.

The characteristic feature of the design resides in the generally triangular protuberance on the front of the luggage case.
